US0D1017981S

(12) United States Design Patent (10) Patent No.: US D1,017,981 S
(45) Date of Patent: * Mar. 19, 2024

(54) SHOE

(71) Applicant: STARLINK TECHNOLOGY CO., LIMITED, Hongkong (CN)

(72) Inventor: Jie Huang, Singapore (SG)

() Term: 15 Years

(21) Appl. No.: 29/911,502

(22) Filed: Sep. 5, 2023

Related U.S. Application Data

(63) Continuation-in-part of application No. 29/854,995, filed on Sep. 29, 2022, now Pat. No. Des. 999,493.

(51) LOC (14) Cl. 02-04

(52) U.S. Cl. USPC D2/925

CLAIM

The ornamental design for a shoe, as shown and described.

DESCRIPTION

FIG. 1 is a perspective view of a shoe showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines and the areas within depict portions of the shoe that form no part of the claimed design.

1 Claim, 8 Drawing Sheets
